UNITED STATES PATENT OFFICE.

PHARES S. HORST, OF EPHRATA, PENNSYLVANIA.

DESIGN FOR A NUT BOWL.

Application filed August 22, 1924. Serial No. 10,517. Term of patent 7 years.

To all whom it may concern:

Be it known that I, PHARES S. HORST, a citizen of the United States, residing at Ephrata, in the county of Lancaster and State of Pennsylvania, have invented a new, original, and ornamental Design for a Nut Bowl, of which the following is a specification, reference being had to the accompanying drawing, forming part thereof.

In the drawings:—

I claim:—

The ornamental design for a nut bowl, as shown.

PHARES S. HORST.
